K. F. Frazer

United States Patent Office.

KASSON FRAZER, OF SYRACUSE, NEW YORK.

Letters Patent No. 65,068, dated May 28, 1867.

IMPROVED SHAFT-TUG.

The Schedule referred to in these Letters Patent and making part of the same.

TO ALL WHOM IT MAY CONCERN:

Be it known that I, KASSON FRAZER, of the city of Syracuse, New York, have invented a new and improved Shaft-Tug; and I do hereby declare that the following is a full, clear, and exact description of the construction of the same, and the form thereof when complete and ready for use, reference being had to the annexed drawings, making a part of this specification, in which—

Figure 1 represents a perspective view, and

Figure 2 a sectional view thereof.

The letters used represent corresponding parts wherever they occur.

To enable others skilled in the art to make and use my invention, I will proceed to describe the construction of the same.

I stitch together or otherwise properly fit up a leather strap, A, of the proper length when doubled together to encircle the shaft, and I enclose the same with a metal band, B. The metal band B is made to pass nearly around the strap A, and to answer the purpose of supporting the strap and holding it to its place, and it also affords a strong bearing for the buckle-bar *a* of the buckle C. I do not make the band to pass entirely around the strap, but leave an opening at *b*, through which the buckle-bar *a* may be made to pass, and thus avoid the necessity of making and fitting a buckle especially for that purpose. Ordinarily any buckle in common use may thus be applied to this invention. I hold the strap A and the band B together by means of rivets *z z z*, using as many as may be needed to firmly keep the parts in place. A loop, *c*, for the belly-band may be added when required.

What I claim as my invention, and desire to secure by Letters Patent, as a new article of manufacture, is—
A shaft-tug composed of the parts A, B, and C, substantially as and for the purposes described.
